UNITED STATES PATENT OFFICE

GEORGES LIAGRE, OF PARIS, FRANCE

ASPIRATOR-VENTILATOR APPARATUS

Application filed December 27, 1927, Serial No. 242,797, and in France January 8, 1927.

The present invention has for object an aspirator-ventilator apparatus which can be used either for salubrity purposes by renewing the air in any medium, or for evacuating vapors and smoke from furnaces or fire-places in general whilst accelerating their draught.

This apparatus is characterized by the combination of the following constituent parts:

1. A central cylindrical body open at both ends and provided with apertures directed upwardly for the entrance and ascent of the outer air;

2. A cap provided with outlet orifices at its upper part and with air inlet orifices at its lower part, in coincidence with the orifices or apertures of the cylindrical body.

The advantages of this apparatus are the following:

1. Absence of any rotary movement which, in certain apparatus, after a very short time, prevents them from rotating owing either to rust, or owing to the agglomeration of soot, or again owing to the corrosive action of vapors, smoke and the like.

2. No longer any rain in the chimneys, the apparatus being covered;

3. Driving back of smoke rendered impossible, as the atmospheric air cannot in any case enter the chimney, since the most violent wind simply accelerates the draught of the latter without ever causing any driving back of smoke, carbon monoxide, vapors or smell;

4. Easy sweeping, owing to the fact that as the cap is removable, it uncovers the central cylindrical body.

The invention will be described, by way of example only, with reference to the accompanying drawing in which:

Fig. 1 is an elevation of a form of construction of this apparatus.

Fig. 2 is a vertical section of the same apparatus.

As illustrated in drawing, this apparatus comprises a cylindrical body *a* arranged on the top of the object adapted to receive it, a closed vehicle for instance.

About this cylindrical body *a* are provided cut out apertures *b* so formed that the flaps

50 cut out at the top remain attached at the bot-

tom to the cylindrical body and are then bent inwardly.

A kind of cap *c*, preferably removable, covers the upper part of the cylinder *a*.

This cap pleated as an accordion is closed at 55 its upper part by a conical cover and its lower part is assembled with the cylindrical body *a*; moreover, cut out apertures *d* with bent flaps are provided in the upper part of the cap; finally, other apertures *e* are provided 60 in the lower part of the said cap by striking in tongues *e'* which serve as baffles and opposite these latter cut out apertures are provided penthouses *f* open at the bottom.

A flange *g* connects in a fluid-tight manner 65 the cylindrical body *a* with the roof *h* of the vehicle for instance.

The bottom part of the cylindrical body *a* is connected to a collar *i* flaring at its lower part and provided with cut out apertures *j*. This 70 collar *i* is secured in the ceiling *k* of the vehicle.

Within the flared portion of the collar *i* is ceiling fixture *l* supporting the lamp and surrounded by an apertured ring *m*.

Vent holes *n* are provided between the roof *h* and the ceiling *k*.

The wind enters through one or the other of the penthouses *f*, according to the direction of running of the vehicle, and thus causes the 80 rapid evacuation of the fumes, smells and vapor of the vehicle through the two outlets *d* provided in the cap.

These two outlets *d* being formed on the sides of the apparatus, neither rain, dust or 85 the like can enter the apparatus.

Moreover, the orifices *n* formed in the bottom portion of the apparatus allow the suction of the foul air which may happen to be between the ceiling *k* and the roof *h*, this attenuating the calorific effect of the solar rays in summer and the action of the cold in winter; finally these orifices regularize the temperature and avoid the expansion and shrinking of the woodwork.

This apparatus will preferably be made of non-oxidable enamelled sheet-iron.

The forms, details, accessories, materials and dimensions of this apparatus can of 100

course be varied without departing thereby from the principle of the invention.

I claim:—

A ventilator of the character described comprising a cylindrical body having the respective ends open and having the lower end in communication with the part to be ventilated, flaps struck inwardly and extended upwardly to leave openings in the body for admitting fresh air, a cap arranged about the upper end of the body and including a conical top and a depending flanged portion accordion shaped in vertical section with the lowermost edge secured to the outer surface 15 of the body, the upper part of the flanged portion having an exit opening therein, flaps struck upwardly at points near the lower edge of the flanged portion and at points near the first flaps so as to leave air admission 20 openings and hoods secured to the outer surface of the flanged portion of the cap and about the last mentioned openings and having the lower ends open.

The foregoing specification of my "Improvements in aspirator-ventilator apparatus" signed by me this 8th day of December, 1927.

GEORGES LIAGRE.
